UNITED STATES PATENT OFFICE.

GEORGE J. CARLISLE, OF NILES, MICHIGAN.

OIL BURNER.

Application filed July 2, 1924. Serial No. 723,669.

To all whom it may concern:

Be it known that I, GEORGE J. CARLISLE, a citizen of the United States of America, and a resident of Niles, Michigan, have invented a certain new and useful Improvement 5 in Oil Burners, of which the following is a specification.

This invention relates to improvements in oil burners and more particularly to burners 10 for house heating furnaces, domestic water heaters and the like, and utilizing kerosene or other suitable hydrocarbon as fuel.

The object of the invention is to provide 15 an improved construction for oil burners in which especial attention has been directed to the design and arrangement of the parts, in order to secure more perfect combustion and a maximum of effective heat, to the end that economy of operation and satisfactory 20 operating conditions can be had at a minimum of expense and attention.

A further object of the invention is to 25 provide an oil burner suitable for house heating, domestic water heating, garages and the like, in which natural draft is utilized 30 for supporting the combustion of the fuel, thus eliminating expensive mechanical equipment for supplying air under pressure, either for promoting combustion or atomizing 35 the fuel. However, a feature of the device is its adaptability to conversion to the atomizer type of apparatus used in industrial burners which can be readily employed where air or steam pressure is available for 40 atomizing purposes.

A preferred embodiment of the invention is illustrated in the accompanying drawings, 45 in which is disclosed an oil burning unit such as would be installed in any suitable 50 form of heating apparatus or forming an integral part thereof.

In the drawings,

Figure 1 is a view in horizontal section 55 taken centrally of the unit as on line 1—1 of Fig. 2.

Fig. 2 is a top plan view of the burner unit with top cover removed.

Fig. 3 is a perspective view of the hot plate removed from the unit.

Fig. 4 is a bottom view of the hot plate.

Fig. 5 is a view in longitudinal section of the fuel nozzle and tubular cap.

Fig. 6 is a cross sectional view of the fuel nozzle and cap, as taken on line 6—6 of

Fig. 5.

Fig. 7 is a perspective view of the fuel nozzle cap.

Fig. 8 is a view in front elevation of the burner unit with parts broken away, and

Fig. 9 is a perspective view of the top plate with baffles attached.

The burner herein disclosed is intended to be mounted in a position corresponding to the fire door of a furnace or heating device, or in such other position as to direct the products of combustion into the space to be heated. As illustrated the shell or casing 1, assumes a horizontal position and opens at its forward end toward the combustion chamber or other space to be heated. The rear half or left hand portion is exterior of the heater. For determining the position of the casing, vertical side flanges 1^a—1^a are provided, which abut against the sides of an opening in the heater into which the casing is inserted.

The casing or shell 1 comprises a box-like casting open at its forward or inner end. The bottom wall 2 is imperforate and has a short upstanding flange 3 across its forward edge. The rear wall 4 is substantially one-half of the height of the casing, and extends upwardly from the bottom wall, the adjacent portions being curved.

A removable top plate 6 rests on the side walls 7, 7 of the casing and forms the top wall, its rear edge being spaced forwardly of the rear walls 4 and its forward edge extended a short distance beyond the front opening of the casing. The top plate is provided with longitudinal ribs 6^a—6^a acting to hold the plate in place.

Secured to the rear edge of the top plate 6 is a depending baffle plate or wall 9 inclined slightly in a forward direction and extending the full width of the casing from side wall to side wall. The lower edge of the baffle terminates a distance above the bottom of the casing and the entire baffle is spaced forwardly of the rear wall 4 thereby dividing the space within the casing into a vertical air passage to the rear, having as its entrance or opening the space between the top edge of the rear wall 4 and the rear edge of the top plate 6. Secured to the lower edge of the baffle wall 9 is another baffle plate 10 extending rearwardly at right angles to said plate 9 and horizontally above the bottom wall. This horizontal baffle 10 abuts against the rear wall 4 and differs

from the vertical baffle 9 in that it is comparatively narrow in width and extends from the central portion of the edge of the vertical plate. The purpose of the horizontal baffle will be hereinafter explained. Mounted in the entrance to the vertical down passage formed by the vertical baffle is a damper 12 to turn on a horizontal transverse axis, by suitable pivot pins 13 mounted in 10 the side walls 7 of the casing.

Resting on the bottom wall of the casing is a hot plate 14, square in shape, to extend the full width of the casing but terminating short of the forward end. A 15 transverse rib 14^c on the bottom of the casing determines the position of hot plate and prevents its movement. By virtue of a longitudinally marginal rib 14^a along the underside of the hot plate the same is elevated above the bottom of the casing. Along the forward edge of the hot plate are notches 14^b while the rear under edge is beveled to conform with the curvature of the casing wall. In the top surface of the hot plate 14 25 is an annular depression or groove 15 having its outer edge spaced a short distance from the front and rear edges of the plate.

Along the rear edge of the hot plate 14 and centrally thereof is a rearwardly projecting lip 16 which extends into a cavity 17 formed at the junction of the bottom and rear walls of the casing and large enough to receive this lip. In the top surface of the lip is formed a channel or depression extending toward and communicating with the annular groove 15 in the top face of the hot plate.

Extending inwardly through the rear wall 4 and in a horizontal direction just above 40 the hot plate 14, is a fuel delivery tube 22 connected with an oil supply pipe 23, leading to a suitable fuel reservoir, there being means employed for supplying the oil to the burner under pressure, although gravity may 45 be used for this purpose. The tube 22 extends forwardly from the rear wall 4 just above the hot plate, with a slight upward inclination, passing beneath the lower edge of the vertical baffle 9 and terminating centrally of the hot plate 14.

Loosely mounted on the tube 22 is a cap-like tube 24 having telescopic and sliding engagement with the first mentioned tube and substantially covers and surrounds the entire 55 length thereof. The forward end of the outer or telescopic tube 24 is closed by means of a cap 24^a, but its inner diameter is somewhat greater than the outer diameter of the tube 22 so that the fuel as it flows from the 60 end of the tube 22 is collected in the outer tube 24 and flows rearwardly in the opposite direction by gravity and trickles from the open end of the outer tube which is located just above the lip 16 at the rear 65 edge of the hot plate, and flows forwardly

again along the channel 16^a into the annular groove 15 for distribution about the heated surface of said plate. As clearly shown in Fig. 5, the outer tube 24 is free to be moved lengthwise on the fixed or inner tube 22, 70 the purpose being to enable the fuel, either to be caught by the lip 16 and distributed to the surface of the hot plate or to be delivered beyond the end of the lip so that it can flow beneath the hot plate and onto the 75 top surface of the bottom wall 2. Thus as clearly illustrated in Fig. 1, the outer tube is positioned so that the fuel flows from the open end thereof onto the lip 16 of the hot plate. However, if the outer tube 24 be 80 shifted rearwardly and to the left so that its open end clears the end of the lip 16, the fuel will obviously drop onto the bottom wall 2 and be carried forwardly beneath the hot plate 14. The purpose of this arrangement will be presently pointed out. 85

The burner as thus far described is complete for ordinary house heating purposes and as such operates with the natural draft created by the heating apparatus. However, 90 as already pointed out the device can be readily converted into an atomizer type of oil burner for larger installations, with the addition of an air pump, or in plants where air or steam pressure is available. To convert the device into an atomizing oil burner, 95 a burner 18 is added which consists of a short piece of pipe having a slotted cap 18^a and which is screwed into a tapped hole in the central portion of the hot plate and 100 extending a short distance below the same.

This burner projects vertically from the hot plate a distance somewhat less than one-half the height of the casing and is positioned just forward of the end of the fuel inlet. Screwed into the bottom wall 2 of the casing just below the burner 18, is a bushing 19 having a cup-like depression 19^a at its upper end flush with the surface of the bottom wall. Tapped into this bushing 110 is a jet nozzle 20 projecting upwardly above the bottom wall, and into the lower end of the burner 18. A pipe 21 is connected with the jet nozzle fitting 20, which leads to a suitable source of air which is forced upwardly through the jet nozzle under pressure by a blower or air pump. If steam is available, it may be used in place of air. These parts can be readily replaced by plugs when 115 not used.

Disregarding for the time being the burner 18, the operation of the device as it would ordinarily be operated will now be described. Assuming that the burner is to be started and all of the parts are cold, the fuel supply is turned on by means of a valve located at a convenient point in the fuel supply pipe 23, thus permitting a small quantity of oil to drip onto the hot plate 14. This fuel is ignited by means of a match, 120

- pilot flame or in any other convenient way, the flame thus ignited gradually spreading and within a comparatively short time heating the hot plate as well as the tube 24.
- 5 During the starting operation the damper 12 would be moved into closed position across the air inlet, and as the flame spreads and becomes more intense the damper is gradually opened to admit a larger quantity 10 of air to support the combustion at the bottom of the casing immediately below the damper. In due time the plate 14 and tube 24 are heated to a high temperature so that the fuel is preheated in passing forwardly 15 through the inner tube 22 and then rearwardly in the outer tube 24 with the result that as it drips onto the hot plate, it vaporizes almost immediately and is ignited. The combustion takes place at the rear of the hot 20 plate and beneath the horizontal baffle plate 10 just above the point of flame propagation, said baffle acting to spread the flames laterally to either side where it mixes with the air drawn downwardly through the air 25 inlet above by the natural draft of the heating apparatus and is swept forwardly beneath the lower edge of the vertical baffle 9 into the combustion chamber forward of said vertical baffle and thence into the space 30 to be heated. It is to be noted that the horizontal baffle plate 10 plays an important part in the maintenance of perfect and complete combustion since it not only spreads the flame laterally thereby affording an opportunity for complete mixture of the flame 35 with the air from above, but prevents the down draft from striking directly against the point of flame propagation with the possibility of extinguishing the flame entirely.
- 40 After the parts have been thoroughly heated to a point at which perfect combustion is maintained, the damper may be utilized for controlling the volume, velocity and direction of the air admitted through the 45 inlet opening. Manifestly by closing the damper the volume of air will be decreased and the velocity increased thus varying the intensity of the heat. Furthermore, by adjusting the position of the damper, the point 50 at which combustion takes place can be shifted, that is to say, the combustion can be delayed so that it does not take place until the mixture has been swept forwardly of the vertical baffle, or it can be advanced so that 55 ignition takes place in the lower portion of the casing rearwardly of the vertical baffle. In this way the operation of the burner can be accurately controlled and economically operated depending upon the heating requirements.
- 60 For normal operation, utilizing the natural draft entirely, the tube 24 of the fuel inlet pipe is positioned forwardly on the inner tube 22 so that the fuel drips onto the hot plate, being delivered thereto by means of the lip 16. If, as before explained, the device is to be operated with the burner 18 attached, whereby the fuel is atomized and forced into the burner, the tube 24 is moved rearwardly and to the left from the position shown in Fig. 1, so that its open end 70 clears the end of the lip 16 thereby permitting the fuel to drip onto the bottom wall of the casing where it flows forwardly and accumulates in the depression 19 of the 75 bushing 19. At this point it is drawn upwardly into the burner by reason of the injector action of the air or steam jet delivered to the burner through the nozzle fitting 20 and pipe 21, mixed with the air or steam and thence discharged through the tip of the burner and ignited, complete combustion being supported by the air which is drawn downwardly through the air inlet 80 opening in the same manner as before described. Thus it will be seen that this operation and a change from one to the other can be easily made.
- 85 The advantage of this particular type of burner resides in the possibility of obtaining perfect combustion and by that is meant the propagation and maintenance of an intense blue flame, which means economy in fuel consumption and efficient heating effect. A further advantage of the device is 90 its adaptability for heating purposes for which the more complicated and expensive burners cannot be employed. This is particularly true of water heaters and other 95 heating plants which ordinarily use gas as the fuel but which heretofore have not been 100 usable in localities in which gas is not available.
- Having described the novel features of 105 construction and the advantages and use of a burner embodying the invention, I claim:
1. An oil burner comprising a casing divided into a forward combustion chamber and a rear air passage communicating with each other near the bottom of the casing, and a fuel inlet to said casing comprising a pipe having forward and return branches extending above the bottom wall of the casing and having its discharge at 110 the rear thereof.
- 115 2. An oil burner comprising a casing opening at one end into the space to be heated and having a substantially vertical baffle spaced rearwardly of said open end, an air inlet on the opposite side thereof, and a fuel inlet pipe extending above the bottom wall to a point forwardly of said baffle and returning to a point rearwardly of said baffle.
- 120 3. An oil burner comprising a casing opening at one end into the space to be heated and having a substantially vertical baffle spaced rearwardly of said open end and an air inlet on the opposite side of said baffle, and a fuel inlet pipe entering from the rear 125 130

of the casing and extending above its bottom wall to a point forward of said baffle and having an inclined return pipe discharging on to the bottom wall rearwardly of said baffle.

4. An oil burner comprising a casing having an opening and directed toward the space to be heated and an air inlet at the opposite end, a baffle dividing said casing into an air passage and a combustion chamber, a hot plate in the bottom of said casing and a fuel inlet pipe extending above said hot plate, and provided with a return pipe discharging on to said plate at the lower end of said air passage.

5. An oil burner comprising a casing having openings at each end and an intermediate baffle depending from the top of said casing, and terminating short of the bottom wall, the space forwardly of said baffle forming a combustion chamber communicating with a vertical air inlet passage rearwardly of said baffle, and a fuel inlet pipe entering said casing from the rear and extending forwardly and above the bottom wall into said combustion chamber and returning to a point adjacent its entrance into said casing.

6. An oil burner comprising a casing open at its forward end and provided with an air inlet at its rear end, a baffle plate depending from the top of said casing and forwardly of said air inlet, a fuel inlet pipe arranged to conduct the fuel into the casing and above the bottom wall thereof, reversing the direction of flow and discharging the same at the rear of said casing, and a damper in said air inlet.

7. An oil burner comprising a casing divided lengthwise into a forward combustion chamber opening toward the space to be heated, and a rear air passage communicating with each other at the bottom of the casing, a damper in said air passage, a hot plate at the bottom of said casing, a fuel inlet pipe entering said casing through the rear wall thereof and extending above said plate into said combustion chamber and provided with a telescopic return tube discharging adjacent the rear edge of said plate.

8. An oil burner comprising a casing opening at its forward end into the space to be heated, a baffle wall depending from the top wall of said casing near the rear end thereof, said casing being provided with an air inlet rearwardly of said baffle, a damper in said air inlet, and a fuel inlet comprising an inner tube extending above the bottom wall and forwardly of said baffle, and an outer return tube mounted on said inner tube and acting to reverse the direction of flow and to discharge the fuel onto the bottom wall rearwardly of said baffle.

65 9. An oil burner comprising a casing, open

at its front end into the space to be heated and having a baffle wall adjacent the rear end thereof, and an air inlet rearwardly of said casing with a combustion chamber and a baffle, a hot plate substantially covering the bottom of the casing, and a fuel intake comprising telescopic tubes extending into said combustion zone from the rear of said casing and having its outlet above said hot plate and adjacent its rear edge.

10. An oil burner comprising a casing open at its forward end toward the space to be heated, the opposite end being located exterior said space and provided at its rear end with an air inlet having a damper therein, a hot plate supported on the bottom of said casing, a baffle plate depending from the top of said casing forwardly of said air inlet, a fuel inlet tube entering said casing from the rear and extending forwardly above said plate, said tube comprising a telescopic member having an outlet opening below said air inlet and rearwardly and above the rear edge of said plate, and a horizontal baffle extending over said fuel outlet.

11. An oil burner comprising a casing having a combustion chamber opening into the space to be heated and an air inlet exterior said space, a depending baffle wall forming a passage connecting said air inlet with said combustion chamber near the bottom of the casing, a hot plate mounted in the bottom of said casing, a fuel inlet pipe extending above said hot plate and terminating centrally thereof, and a return tube telescopically mounted on said pipe tube and acting to discharge the fuel onto the rear edge of said hot plate, a baffle plate extending transversely of said air passage and above said fuel pipe, and a damper in said air passage.

12. An oil burner comprising a casing having an open forward end directed toward the space to be heated and an air inlet at its rear end communicating with the air exterior the space to be heated, a depending baffle forwardly of said air inlet, a hot plate supported on the bottom wall of the casing, a burner projecting from the central portion of said plate and communicating with the space between the bottom wall and said hot plate, a jet nozzle directed axially of said burner, a fuel intake tube extending above said hot plate and comprising a telescopic member directing the flow of the fuel onto the rear edge portion of said hot plate, and shiftable to permit the fuel to flow beneath said plate whereby the same is delivered to said burner.

13. An oil burner comprising a casing open at its forward end toward the space to be heated, the opposite end being located exterior said space and provided at its rear end with an air inlet having a damper

- therein, a baffle plate depending from the top of said casing forwardly of said air inlet, a plate supported on the bottom wall of said casing, a burner extending through 5 said plate and communicating with the space between said plate and bottom wall, means for injecting air into said burner, a fuel inlet tube entering said casing from the rear and extending forwardly above said 10 plate, said tube comprising a telescopic member having an outlet opening below said air inlet rearwardly and above the rear edge of said plate and adjustable lengthwise to direct the flow of fuel to the space beneath 15 said plate.
14. An oil burner comprising a casing having a combustion chamber opening into the space to be heated, and an air inlet exterior said space, a baffle wall forming a 20 vertical passage connecting said air inlet with said combustion chamber near the bottom of the casing, a hot plate mounted in the bottom of said casing, a burner mounted centrally of said plate and opening into the 25 space below said plate, an air jet in said burner, a fuel inlet pipe extending above said hot plate and terminating centrally
- thereof, and a return tube telescopically mounted on said pipe tube and adapted to be shifted lengthwise to discharge the fuel 30 onto said plate or beyond the edge of said plate thereby supplying fuel to said burner.
15. An oil burner comprising a casing having an open forward end directed toward the space to be heated, and an air inlet at 35 its rear end communicating with the air exterior the space to be heated, a depending baffle forwardly of said air inlet, a hot plate supported on the bottom wall of the casing, a burner projecting from the central portion 40 of said plate and communicating with a depression in the bottom wall below said hot plate, a jet nozzle directed axially of said burner, a fuel intake tube extending above said hot plate and comprising a telescopic 45 return pipe member normally directing the flow of the fuel onto the rear edge portion of said hot plate but adapted to be shifted to permit the fuel to be discharged onto the bottom wall and thence to flow into the depression therein. 50

Signed at Chicago, Ill., this 24th day of June, 1924.

GEORGE J. CARLISLE.
